UNITED STATES PATENT OFFICE

2,004,692

REFRIGERATOR

George E. Friedrich, San Antonio, Tex., assignor
to Edward Friedrich, San Antonio, Tex.

Application December 4, 1934, Serial No. 755,954

7 Claims. (Cl. 62—102)

My invention relates to certain new and useful improvements in refrigerators of the general type disclosed in Letters Patent No. 1,893,769, issued January 10, 1933, and it primarily has for its object so to modify and improve the patented refrigerator as to obtain greater efficiency and more uniform temperature throughout the refrigerating compartment of the cabinet or case. While the refrigerator of Letters Patent No. 1,893,769 was a considerable step in advance in the art, I find that by the construction, arrangement and combination of the parts herein shown and described in this application I am enabled to effect an equalization of the temperature throughout the cabinet or case within four degrees at any given points, while with the construction as shown in Letters Patent No. 1,893,769 the equalization is only within seven or eight degrees.

Other objects will in part be obvious and in part be pointed out hereinafter.

To the attainment of the aforesaid objects and ends, the invention still further resides in the novel details of construction, combination and arrangement of parts, all of which will be first fully described in the following detailed description and then be particularly pointed out in the appended claims, reference being had to the accompanying drawings, in which:

Figure 1 is a vertical longitudinal section on the line 1—1 of Figure 2.

Figure 2 is a cross section on the line 2—2 of Figure 1, looking in the direction of the arrow.

Figure 3 is a horizontal section on the line 3—3 of Figure 1.

Figure 4 is a vertical section on the line 4—4 of Figure 1.

Figure 5 is a detail sectional perspective view of one of the pans.

In the drawings, in which like numerals and letters of reference indicate like parts in all the figures, it will be observed that the base of the cabinet is composed of a bottom board or facing 1, a top facing 2, and an interposed cork or other suitable insulation material 3.

The front wall of the cabinet is composed of a vertical facing 4 and an upwardly and rearwardly inclined facing 5 with bottom and top sills 6 and 7 and side standards 64 which constitute the window frames for the window glasses 60, hereinafter again referred to. 8 indicates cork insulation beneath the sill 6 and constitutes part of the front wall of the cabinet.

The rear wall of the cabinet is composed of an outer facing 9, an inner facing 14, and interposed insulation 15 of cork or other suitable material,

the rear wall including door frames 10 and 11 for the lower and upper doors 12 and 13 respectively. 16 designates a partition running lengthwise of the cabinet and spaced from the cork wall 8 to provide a bottom air collecting duct 17, the top of which is closed by a plate 18. The partition 16 extends from adjacent one end of the cabinet toward the other end and at the other end there is provided a cross partition 19 which leaves a blower chamber 22 with which the duct 17 communicates. The blower chamber 22 is closed at the top by board 20 and the partition 19 has an opening 21 through which the spout 24 from the blower casing 23 passes. The blower casing 23 is located in the blower chamber 22 and contains a turbine or blower 25 which is driven by a motor 20.

29 designates the air distributing duct, one end of which connects to the nozzle 24, while the other end is closed and terminates adjacent the opposite side wall of the cabinet. The duct 29 is composed of a bottom plate 27 and a top plate 28, the latter being perforated so that air may pass upwardly therethrough.

The duct 29 is located between longitudinal cleats 30 that are located adjacent the insulation 15 and partition 16 respectively (see Figure 2). Above the duct 29 is the air cooling chamber 31 in which is located the cooling means. The cooling means in the present structure is disclosed as a cooling coil unit 32 of any approved construction.

Resting on the plate 18 and on an angle bracket 33, which is secured to the facing 14 of the rear wall, is a series of pans 34 the construction of which is best indicated in Figures 1, 2 and 5. 35 These pans have upstanding walls 35 and horizontal flanges 36, one being somewhat longer than the other and turned down to provide a short vertical flange 37 to hook over the flange 36 of a succeeding pan. The pans also have side walls 38 and are provided with flanges 39 one of which rests on the angle bar 33.

The upstanding walls 35 and 38 are perforated as at 40 to permit air circulation.

Placed above the pans 35 is a foraminous floor 41, preferably formed of crossed wires, which constitutes the bottom shelf of the cooling compartment of the cabinet.

Located between the upper and lower door levels is a longitudinal vertical duct 42 having vertical 50 extensions or branches 42 located between the adjacent upper doors. These branches 43 are provided with air holes 44 through which warm air at the top of the cabinet may be drawn into the ducts 43—42. The duct 42 extends the entire 55

length of the cabinet and communicates at its ends with the lower portions 52 and 54 of the end down-air ducts (see Figure 1).

Mounted on a suitable support 47 is an approximately horizontally disposed, longitudinal, return air duct 45 which also serves as the top shelf on which the food containing pans 61 are held (see dotted lines, Figure 2). The duct 45 is inclined slightly to the horizontal and pans 61 are held 10 from sliding off by a pan stop 50. The duct 45 at its sides has air openings 46 through which air is drawn into the duct. The duct 45 also extends the full length of the cabinet and at its ends communicates with the upper portions 51 and 53 of 15 the end down-air ducts. The intermediate shelf 49 is composed of crossed wires and is held on suitable supports 48. The supports 48 and 47 may be integral with or formed as brackets which are secured to the ducts 42-43 by welding or in any 20 other suitable desired way.

55 is the top plate of the cabinet over which the top glass 59 lies, the top of the cabinet being transparent and provided with a series of glasses, 59, as shown in Figures 1 and 2. The top wall of 25 the cabinet is also provided with insulation 56, best shown in Figure 2.

The end walls of the cabinet are composed of outer facings 65 and cork insulation 57, the cork insulation 57 embedding the down-air ducts, the 30 inner walls of which ducts constitute the inner facings or linings of the end walls of the cabinet, the lining of the top of the cabinet being indicated by 63. The front glass plates 60 have disposed between them the usual dehydrating tubes 62.

35 In order to support the pan 34 which is adjacent the wall 19, the lining 61 over the blower compartment is extended down and provided with a horizontal angle portion 66 on which the pan may rest.

40 So far as described, the manner in which the invention operates is as follows:

Assume the motor to be energized to drive the turbine; the warmer air is drawn into the ducts 43 and 45, passing into the ends of the ducts 51, 45 52 and 53, 54 down which the air currents pass. The air passing down through the end duct 51-52 is drawn into the longitudinal duct 17 and passes along it into the blower compartment 22, while the air passing down the duct 53-54 is delivered 50 directly into the blower compartment 22, from which compartment the air is drawn into the blower housing 23 and driven out by the blower through the nozzle 24 into the distributing duct 29. From the duct 29 the air passes through the perforated top 28 of the duct and through the cooling compartment 31, from whence it passes 55 through the apertured pans and floor 41 into the food chamber of the case, thus completing the cycle.

60 It will be noted that the duct 17 is enclosed completely from the cooling compartment 31 and from the air distributing duct 29, and the air is carried in the duct 17 the full length of the case to the blower compartment 22 where it is propelled into the duct 29 underneath the cooling coil, as before described.

Actual tests with a refrigerator made in accordance with the drawings and description of this application have shown that the temperature throughout the interior chamber of the cabinet 70 does not vary more than four degrees between any two points, which makes for a very efficient operation of the refrigerator.

From the foregoing description, taken in connection with the accompanying drawings, it is

thought that the complete construction, operation and advantages of the invention will be clear to those skilled in the art.

What I claim is:

1. In a refrigerator, a cabinet having a food compartment which extends substantially the full length and depth and height of the cabinet, a floor for said compartment having air passages, an air collecting duct and a cooling chamber extending lengthwise of the cabinet beneath the floor, cooling means in said cooling chamber, a blower chamber at one end of said cabinet with which one end of said air collecting duct communicates, a down-air duct located at each end of the cabinet, said air collecting duct communicating at one end with one of said down-air ducts and communicating at the other end with said blower chamber, a blower in said blower chamber, an air delivery duct extending from said blower beneath said cooling chamber 20 and terminating adjacent the opposite end of the cabinet and having a foraminous top to deliver air into said cooling chamber, an approximately horizontal combined food shelf and return air duct extending lengthwise in said compartment, spaced below the top thereof and communicating at its ends with said down-air ducts respectively. 25

2. In a refrigerator, a cabinet having a food compartment which extends substantially the full length and depth and height of the cabinet, a floor for said compartment having air passages, an air collecting duct and a cooling chamber extending lengthwise of the cabinet beneath the floor, cooling means in said cooling chamber, a blower chamber at one end of said cabinet with which one end of said air collecting duct communicates, a down-air duct located at each end of the cabinet, said air collecting duct communicating at one end with one of said down-air ducts and communicating at the other end with said blower chamber, and a blower in said blower chamber, said cabinet having door openings, vertical ducts between the adjacent door openings and having air inlets adjacent the top of said ducts, a vertical longitudinal duct into which said vertical ducts deliver, the ends of said vertical longitudinal duct communicating with said down-air ducts respectively. 40

3. In a refrigerator, a cabinet having a food compartment which extends substantially the full length and depth and height of the cabinet, a floor for said compartment having air passages, an air collecting duct and a cooling chamber extending lengthwise of the cabinet beneath the floor, cooling means in said cooling chamber, a blower chamber at one end of said cabinet with which one end of said air collecting duct communicates, a down-air duct located at each end of the cabinet, said air collecting duct communicating at one end with one of said down-air ducts and communicating at the other end with said blower chamber, a blower in said blower chamber, an air delivery duct extending from said blower beneath said cooling chamber and terminating adjacent the opposite end of the cabinet and having a foraminous top to deliver air into said cooling chamber, an approximately horizontal combined food shelf and return air duct extending lengthwise in said compartment, spaced below the top thereof and communicating at its ends with said down-air ducts respectively, said cabinet having door openings, vertical ducts between the adjacent door openings and having air inlets adjacent the top of 55 60 65 70 75

said ducts, a vertical longitudinal duct into which said vertical ducts deliver, the ends of said vertical longitudinal duct communicating with said down-air ducts respectively.

- 5 4. In a refrigerator, a cabinet having doors in one of its walls, a vertical longitudinal air duct extending beneath the door level and having vertical branches located between adjacent door positions, the vertical branches having air inlets
10 adjacent their tops, a down-air duct located in each end wall of the cabinet with which down-air ducts the ends of said vertical longitudinal air duct communicate, a blower chamber adjacent the bottom of the cabinet with which the
15 end of one of said down-air ducts communicates, a return air duct extending from the bottom of said other down-air duct to said blower chamber, an air delivering duct extending alongside said return air duct at the bottom of said cabinet and having its upper wall perforated, cooling means above said perforated wall, and a floor having air passages and located above said cooling means.

25 5. In a refrigerator, a cabinet having doors in
one of its walls, a vertical longitudinal air duct
extending beneath the door level and having ver-
tical branches located between adjacent door po-
sitions, the vertical branches having air inlets
adjacent their tops, a down-air duct located in
30 each end wall of the cabinet with which down-air
ducts the ends of said vertical longitudinal air
duct communicate, a blower chamber adjacent
the bottom of the cabinet with which the end
of one of said down-air ducts communicates, a
35 return air duct extending from the bottom of said
other down-air duct to said blower chamber, an
air delivering duct extending alongside said re-
turn air duct at the bottom of said cabinet and
having its upper wall perforated, cooling means
40 above said perforated wall, a floor having air pas-
sages and located above said cooling means, and a
series of pans having air passages and being
located between said floor and said cooling means.

45 6. In a refrigerator, a cabinet having doors in one of its walls, a vertical longitudinal air duct

extending beneath the door level and having vertical branches located between adjacent door positions, the vertical branches having air inlets adjacent their tops, a down-air duct located in each end wall of the cabinet with which down-air ducts the ends of said vertical longitudinal air duct communicate, a blower chamber adjacent the bottom of the cabinet with which the end of one of said down-air ducts communicates, a return air duct extending from the bottom of said other down-air duct to said blower chamber, an air delivering duct extending alongside said return air duct at the bottom of said cabinet and having its upper wall perforated, cooling means above said perforated wall, and a floor having air passages and located above said cooling means, said cabinet having a shelf spaced from the top of the cabinet and comprising a return air duct whose ends are connected to said down-air ducts.

7. In a refrigerator, a cabinet having doors in 20
one of its walls, a vertical longitudinal air duct
extending beneath the door level and having vertical
branches located between adjacent door positions,
the vertical branches having air inlets 25
adjacent their tops, a down-air duct located in
each end wall of the cabinet with which down-
air ducts the ends of said vertical longitudinal air
duct communicate, a blower chamber adjacent
the bottom of the cabinet with which the end of
one of said down-air ducts communicates, a return
air duct extending from the bottom of said 30
other down-air duct to said blower chamber, an
air delivering duct extending alongside said return
air duct at the bottom of said cabinet and
having its upper wall perforated, cooling means
above said perforated wall, a floor having air passages
and located above said cooling means, said cabinet
having a shelf spaced from the top of the 35
cabinet and comprising a return air duct whose
ends are connected to said down-air ducts, the
shelf-duct being inclined, and means along the
low edge of the shelf-duct to hold food containers
on the same 40

GEORGE E. FRIEDRICH
